UNITED STATES PATENT OFFICE.

HENRY E. MAURER, JR., OF SPRINGFIELD, ILLINOIS, ASSIGNOR OF ONE-HALF TO
HARRY L. IDE, OF SPRINGFIELD, ILLINOIS.

APPARATUS FOR DISPENSING LIQUID.

1,308,091.

Specification of Letters Patent.

Patented July 1, 1919.

Application filed December 10, 1918. Serial No. 266,045.

To all whom it may concern:

Be it known that I, HENRY E. MAURER, Jr., citizen of the United States, residing at Springfield, in the county of Sangamon and State of Illinois, have invented a certain new and useful Improvement in Apparatus for Dispensing Liquid, of which the following is a full, clear, concise, and exact description.

10 My invention relates to apparatus for dispensing liquids and has a number of objects and advantages in view.

One object of my invention is to provide unitary valve mechanism having a number 15 of valve portions operated in proper order to control the admission of liquid to and its discharge from containers. The invention also has other characteristics and will be fully explained by reference to the accompanying drawings in which Figure 1 is a view, somewhat diagrammatic, illustrating the preferred embodiment of the invention, views of the valve mechanism being taken on line A—A, B—B and C—C of Fig. 5; 20 Figs. 2, 3 and 4 are views, somewhat diagrammatic, of parts illustrated in Fig. 1 showing different valve adjustments; Fig. 5 illustrates a unitary valve structure embracing the valve elements shown in Figs. 1 to 30 4 inclusive; Fig. 6 is a view on line 6—6 of Fig. 5; and Fig. 7 is a side view of parts of the valve structure.

Like parts are indicated by similar characters of reference throughout the different figures.

The container 1 is desirably in the form of an inverted glass bottle. As I have practised my invention the bottle is of five gallon capacity. Gage marks 2, corresponding to other measured quantities of liquid within the bottle, may be suitably provided, as by means of marks molded upon the bottle. The bottle neck 3 is received in an annular or tubular seat 4 whose bore is in direct 45 communication with the bore of the bottle neck to afford direct passage for liquid through the bottom of the container, the bottle neck, not only outwardly in the dispensation of the liquid from the container, 50 but also inwardly to replenish the supply of liquid within the container.

The gasoline or other liquid is supplied to the container from a supply tank 5 which is vented, as at 6. The liquid flows 55 from the tank to the container through the

pipe 7 and flows from the container through the eduction nipple 8 and the discharge hose 9 connected with this nipple. The container may be drained or emptied back into the tank through the by-pass 10 that connects the passage 3 with the pipe 7, it being desirable to do this when the apparatus is out of service, as at night. A suction-vent tube 11 is preferably within and extends to the top of the container. When liquid is being discharged from the container, this tube is thrown into communication with the external air to act as a vent. When liquid is being passed into the container, this tube is thrown into communication with the air exhaust pump 12 or the vacuum tank 13 in which vacuum is maintained by said pump.

The valve 14 serves, according to its adjustment, to seal the inlet-outlet end 3 of the container, or to establish connection between the container and the discharge hose and then to cut off communication between the supply tank and container, or to establish connection between the container and supply tank and then to cut off communication between the container and discharge hose. The valve 15, according to its adjustment, establishes or breaks the continuity of the by-pass 10. The valve 16, according to its adjustment, establishes or breaks connection between the vent tube 11 and the external air; or establishes and breaks connection between said vent tube and the vacuum tank.

All of said valves are formed in a unitary structure, as shown in Fig. 6, such unitary structure being preferably a single piece of brass 17 suitably ported to have it form all of the valves, the composite valve 17 operating in a single valve casing 18, that is ported correspondingly to said valve. This composite valve and its casing are tapered, a spring 19 serving to hold the valve in snug engagement with its casing to avoid leakage. The valve is provided with a handle 20 having a spring pressed plunger detent 21 for holding the handle and valve in the position to which it is adjusted. The handle sweeps over a dial 22 having notches 23 for receiving the detent 21, these notches being positioned at the different places to which the composite valve is to be adjusted to secure the desired control and association of the container inlet-outlet 3. In Fig. 1 the valve handle is shown at the notch marked 110

"Hose" establishing a valve adjustment that limits the container to connection with the delivery hose 9; and the external air, as clearly shown in Fig. 1. When the valve handle is placed at the notch marked "To hold" the valve adjustment shown in Fig. 2 is secured. By this adjustment the container is shut off from communication with the hose and the supply tank. When the bottle is to be filled the valve handle is placed at the notch marked "To fill bottle" (Fig. 3) to bring the container opening 3 into communication with the supply tank 5 and the upper end of the bottle into communication with the vacuum tank 13 by way of the tube 11 to exhaust air from the upper end of the bottle to occasion flow of the gasoline or other liquid upwardly into the bottle from the supply tank. When the bottle is to be drained the valve handle is placed at the notch marked "To drain" whereby the adjustment illustrated in Fig. 4 is secured. By this adjustment the tube 11 is thrown into communication with the external air and the continuity of the by-pass 10 is established, whereupon all of the liquid remaining in the container is discharged through the pipe 7 back into the tank 5.

The tube 11 is connected with the valve chamber 24. A float 25 is located within the valve chamber and carries the valve 26 for engagement with the seat 27 when connection with the vacuum tank 13 is to be cut off, this valve being separated from its seat when communication between the container and the vacuum tank is to be established. When the container is about filled a small portion of the liquid will flow downwardly through the tube 11 into the valve chamber 24 and when received in sufficient quantity within this chamber the float 25 will rise to engage the valve 26 with its seat 27 whereby communication between the vacuum tank and the container is automatically cut off to cause the cessation of upward flow of liquid from tank 5 into the container. The small portion of liquid remaining in the valve chamber 24 and the tube 11 at the conclusion of each filling operation is sufficiently sucked back into the container to lower the float as the liquid comes to its normal upper level, whereby the valve 26 is automatically opened to permit the valve 16 to function.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:

1. Liquid dispensing apparatus including a dispensing liquid container; means for in-

troducing liquid into the container; means for exhausting air from the container; means enabling the discharge of liquid from said container; a unitary valve structure having valve formations respectively individual to said means to control the functioning thereof; a valve for checking the exhaustion of air from the container; and a chamber for the valve in communication with the upper portion of the container to receive liquid from such upper container portion, said valve being movable to a checking position by the liquid received in said chamber. 70

2. Liquid dispensing apparatus including a dispensing liquid container; means for introducing liquid into the container; means for exhausting air from the container; means enabling the discharge of liquid from said container; and a unitary valve structure having valve formations respectively individual 75 to said means to control the functioning thereof. 80

3. Liquid dispensing apparatus including a dispensing liquid container; means for introducing liquid into the container; means 90 for exhausting air from the container; means enabling the discharge of liquid from said container; a unitary valve structure having valve formations respectively individual 95 to said means to control the functioning thereof; a valve for checking the exhaustion of air from the container; a chamber for the valve in communication with the upper portion of the container to receive liquid from such upper container portion, said valve being movable to a checking position by the liquid received in said chamber; a by-pass for establishing communication between said container and supply tank; and a valve in the by-pass and included in said 100 unitary valve structure. 105

4. Liquid dispensing apparatus including a dispensing liquid container; means for introducing liquid into the container; means for exhausting air from the container; means 110 enabling the discharge of liquid from said container; a unitary valve structure having valve formations respectively individual to said means to control the functioning thereof; a by-pass for establishing communication between said container and supply tank; and a valve in the by-pass and included in said unitary valve structure. 115

5. Liquid dispensing apparatus including a container having an opening in its lower 120 end through which liquid may be taken into and discharged from the container; a supply tank connected with said opening in the container; a by-pass connecting said opening in the container with the supply tank; and a 125 valve in said by-pass.

6. Liquid dispensing apparatus including a dispensing liquid container; means for introducing liquid into the container; means for exhausting air from the container; 130

- means enabling the discharge of liquid from said container; a unitary valve structure having valve formations respectively individual to said means to control the functioning thereof; and ported to establish communication between the container and the external air when communication with the means for exhausting air from the container is cut off and to cut off communication between the container and the external air when communication between the container and the air exhausting means is established; a valve for checking the exhaustion of air from the container; and a chamber for the valve in communication with the upper portion of the container to receive liquid from such upper container portion, said valve being movable to a checking position by the liquid received in said chamber.
20. 7. Liquid dispensing apparatus including a dispensing liquid container; means for introducing liquid into the container; means for exhausting air from the container; means enabling the discharge of liquid from said container; and unitary valve structure having valve formations respectively individual to said means to control the functioning thereof, and ported to establish communication between the container and the external air when communication with the means for exhausting air from the container is cut off and to cut off communication between the container and the external air when communication between the container and the air exhausting means is established.
25. 8. Liquid dispensing apparatus including a dispensing liquid container; means for introducing liquid into the container; means for exhausting air from the container; means enabling the discharge of liquid from said container; a unitary valve structure having valve formations respectively individual to said means to control the functioning thereof; and ported to establish communication between the container and the external air when communication with the means for exhausting air from the container is cut off and to cut off communication between the container and the external air when communication between the container and the air exhausting means is established; a by-pass for establishing communication between said container and supply tank; and a valve in the by-pass and included in said unitary valve structure.
30. 9. Liquid dispensing apparatus including a dispensing liquid container; means for introducing liquid into the container; means for exhausting air from the container; means enabling the discharge of liquid from said container; a unitary valve structure having valve formations respectively individual to said means to control the functioning thereof, and ported to establish communication between the container and the external air when communication with the means for exhausting air from the container is cut off and to cut off communication between the container and the external air when communication between the container and the air exhausting means is established; a by-pass for establishing communication between said container and supply tank; and a valve in the by-pass and included in said unitary valve structure.

In witness whereof, I hereunto subscribe my name this fourteenth day of Sept., A. D. 1918.

HENRY E. MAURER, JR.
